Patented Dec. 5, 1922.

INVENTOR

Melachiel Nusim

Herbert Golden
BY
his ATTORNEY

UNITED STATES PATENT OFFICE.

MELACH J. NUSIM, OF EASTON, PENNSYLVANIA, ASSIGNOR TO INGERSOLL-RAND COMPANY, OF JERSEY CITY, NEW JERSEY, A CORPORATION OF NEW JERSEY.

IMPELLER.

Application filed March 31, 1921. Serial No. 457,272.

To all whom it may concern:

Be it known that I, MELACH J. NUSIM, a citizen of the United States, a resident of Easton, county of Northampton, and State of Pennsylvania, have invented a certain 5 Impeller, of which the following is a specification, accompanied by drawings.

This invention relates to impellers for centrifugal blowers, compressors and the 10 like, but more particularly to a single or double flow impeller adapted for axial intake and radial discharge. An impeller of the open type is shown, but the invention may be applied to the closed type.

15 In an impeller of the type to which this invention relates, the web is provided with blades having intake portions for receiving the air or other gas by an axial approach, and velocity is imparted to the air by radial 20 blade portions, having exit edges at their peripheries.

The objects of the invention are to strengthen and stiffen the blades and impeller structure by simple means which 25 cheapen the cost of manufacture, and at the same time produce more efficient results for the reasons which will appear upon consideration of my drawings, specification and claim.

30 The invention is illustrated in one of its preferred forms in the accompanying drawings, in which

Figure 1 is a top plan view of an impeller embodying the invention.

35 Figure 2 is a side elevation of a portion of the impeller illustrating the construction.

Figure 3 is a transverse vertical sectional view of Figure 2 on the line 3-3 looking in the direction of the arrows.

40 Figure 4, is a detail plan view of one of the blades before being bent into final form, and

45 Figure 5, is a detail perspective view of the blade shown in Figure 4 in final form for use in the impeller.

Referring to the drawings, the impeller A is mounted on the shaft B and rotates in the casing C, a portion only of which is indicated. The impeller comprises a hub portion D, a circular web E and blades F and the hub portion as shown is thickened and merges into the thinner web in a gradual

curve, these parts preferably being integral and formed in one piece.

The blades F are separated from the hub 55 and web but adapted to be secured thereto, and in accordance with this invention, the blades are provided with securing flanges preferably formed by bending the inner edges of the blades substantially throughout 60 their length at an angle to the surfaces of the blades. The metal of the flanges is crimped or otherwise shaped at the curved portions H of the blades to conform to the curvature of the hub and web and the intake portions J of the blades lie in part directly upon the thickened hub portion and are bent transversely to the axis of rotation in order to increase the intake effect on an axial approach and scoop in the air or gas, 70 as the term may be used. The intake portions J also preferably project beyond the hub portion in an axial direction. The radial portions K of the blades, preferably extend substantially to the periphery of the 75 web E at which the exit edges L of the blades are located. The flanges G may be riveted or otherwise secured to the web and hub.

The construction is light, stiff and strong 80 and presents substantially smooth unbroken working surfaces to the air or gas, since each blade is a unit made up of one piece, and the hub and web together form one piece.

I claim:

An impeller for centrifugal blowers, compressors and the like, adapted for axial intake and radial discharge, and comprising a thickened hub portion having a thinner 90 circular web extending transversely to the longitudinal axis of the hub and merging into the hub in a gradual curve, said web tapering gradually from the hub portion to the periphery of the web, and blades extending from the base of the said thickened hub portion along the sides of the said hub and web to the periphery of the web, and provided with inner intake portions lying in part directly upon the thickened hub portion and bent transversely to the longitudinal axis of the hub, and projecting beyond the hub portion in an axial direction, the outer portions of the blades extending radi-

ally, and the exit edges terminating substantially at the periphery of the said web, the inner edges of the blades along both the intake and radial portions being bent substantially at right angles to the surfaces of the blades to form flanges for securing the blades to both the hub and the web, and the

metal of said flanges being shaped to conform to the curved contour of the hub.

In testimony whereof I have signed this 10 specification.

MELACH J. NUSIM.
